MULTI-COMPARTMENT BULK STATION

Walter J. Sackett, Sr., Baltimore, Md., assignor to The A. J. Sackett & Sons Company, Baltimore, Md., a corporation of Maryland

Filed June 6, 1961, Ser. No. 115,203

5 Claims. (Cl. 214—16)

This invention relates generally to bulk storage and selective dispensing units, and more particularly it pertains to a packaged multi-compartment storage elevator of versatile utility and function.

In the past it has been necessary to obtain blended materials, such as stock feeds and fertilizers from large established mixing plants. This practice involves expensive transportation of the final product which is in addition to the costs of transportation of the raw materials.

Costs to the customer are reduced where large quantities are involved as in concrete road building by locating the "plant" at the construction site. The setting up of such a field facility is only economical in cases of large magnitude and rules out lesser agencies such as farmers' co-operatives and feed and supply stores.

These types of users cannot afford to set up multiple units including the usual unloaders, storage bins, conveyors, weighing stations, and blender machines which make up the usual plant.

Accordingly, it is an object of the present invention to provide a bulk storage station which performs all the functions of a complete blending plant for mixed materials in one readily set up unit.

Another object of this invention is to provide a complete bulk storage unit which dispenses any desired blend of stored materials on a short-order or a deferred time basis as desired.

Still another object of this invention is to provide an easily erected receiving and dispensing station for side track use which receives and stores bulk materials and serves accurately mixed blends with a minimum of handling and with a minimum of personnel.

These and other objects and attendant advantages of this invention will become more readily apparent and understood from the following detailed specification and accompanying drawings in which:

FIG. 1 is a side elevation of a multi-compartment bulk station incorporating patentable features of this invention;

FIG. 2 is a plan view of the bulk station shown in FIG. 1;

FIG. 3 is an expanded vertical section of a silo portion of the bulk station;

FIG. 4 is a view taken along the line 4—4 of FIG. 3 showing details of a valve plate;

FIG. 5 is a detail view along the line 5—5 of FIG. 3;

FIG. 6 is a detail view, looking downwardly, taken along the line 6—6 of FIG. 3; and

FIG. 7 is a detail view, looking upwardly, taken along the line 7—7 of FIG. 3.

Referring now to the details of the drawings as shown in FIG. 1, the bulk station of this invention is designated generally by reference numeral 10. This bulk station 10 is intended to be set up adjacent a convenient railway spur track consisting of spaced rails 14. Thus, hopper cars 16 can be shunted alongside the bulk station 10 to be unloaded into a vertical elevator 20. The elevator 20 is mounted in a shallow pit lined with a steel box 21 so that its receiving chute 18 is approximately at ground level.

As best shown in FIG. 2, spill aprons 52 and 54 are provided on opposite sides of the rails 14 upon which a top-of-track conveyor 12 is placed to extend beneath the hopper car 16 and terminate at the receiving chute 18.

The elevator 20 is secured to the side of a cylindrical

2

silo 26 which rests in an elevated position on a foot plate 110 atop supporting columns or structure 29. A gravity chute 22 extends from the top of the elevator 20 to a point directly over the axis of the silo 26 where it attaches to a bin selector 24. A foot plate 110 is provided which supports a truncated cone 30 which communicates with and depends beneath the silo 26.

The silo 26 is demountable, preferably being made of staves 112 bound together with hoops 114 while the cone 30 may advantageously be made from sheet steel and sectionalized for ease of transportation and set-up.

The silo 26 and the cone 30 are radially divided into a plurality of compartments with the lower cone compartments 32 forming contiguous extensions of the upper silo compartments 28.

As shown best in FIGS. 1 and 3, a tubular mast 74 is positioned axially within the silo 26 and it extends from the top thereof to a valve plate 94 attached to the small end of the truncated cone 30.

This mast 74 is divided into an upper column 76 and a lower column 86 secured together by flanges 84 and 88 with nuts and bolts 90.

Dividers 33 which form the compartments 32 of the cone 30 are secured by bolting or otherwise both to the column 86 and to the inside of the cone 30.

The dividers 31 which form the compartments 28 of the silo 26 are best made of wood planks 132, as shown in FIGS. 5 and 6.

These planks 132 are set edgewise and secured at their inner ends by spaced flanges 128 which are attached around the upper column 76 and at their outer ends in channels formed by spaced vertical guides 130 bolted to the staves 112 of the silo 26 as shown best in FIGS. 5, 6, and 7.

Each compartment 32 is provided with a hydraulically operated compartment gate 34 mounted on a common radius upon the underside of valve plate 94. A centering cone 38 is positioned directly beneath this array of gates 34.

As best shown in FIGS. 3 and 4, a flange 92 is secured to the center of the valve plate 94 by nuts and bolts 96. In addition to forming a supporting base for the column 86, this flange 92 performs two other functions, namely that of a shaft journal and of a detent plate.

A lower stub shaft 98 is vertically journaled in the center of this flange 92, and it rotates a connecting shaft 100 which extends upwardly through the mast 74. An upper stub shaft 68 is secured to the upper end of the connecting shaft 100 and it is journaled in and extends through a plate 78 which is attached to the top end of the upper column 76 with gussets 82.

The previously mentioned bin selector 24 is secured to this stub shaft 68 and it can be rotated by manually positioning a compartment selector lever 36 attached to the lower stub shaft 98. This lever 36 is pivoted on a hinge pin 102 and its weight urges a latch pin 104 upwardly in a guide 106 so as to engage in detent fashion one of a series of spaced latching apertures 108, 108', or 108'' in circular array in the flange 92.

The silo 26 is provided inside near its top with a roof support ring 116 on which roof planks 118 are supported. These planks 118 have an over all waterproofing 124 and terminate short of the center of the silo 26 to provide a circular opening 122 framed by a thick ring 120. A hood-like rain shield 126 forming part of bin selector 24 extends over this ring 120.

The chute 22 enters a rotary slip joint 58 located in the center of the rain shield 126 and thence communicates with an angled distributing spout 56. The spout 56 is fastened by means of a bracket 60 to a bearing assembly 62 consisting of an upper plate 64 and a lower plate 66 spaced with gussets 70.

The lower plate 66 and gussets 70 are welded to the previously mentioned upper stub shaft 68 and thus the bearing assembly 62 can rotate on the plate 78 and be supported by the mast 78. A grease fitting 72 and thrust bearing 80 are provided to reduce the friction at the contact area.

As shown in FIG. 1, a platform 44 for operators of the bulk station 10 is attached to the supporting structure 29. This platform 44 also serves to support a weight-blender 40 which is disclosed in a copending U.S. patent application Serial Number 43,838, now Patent No. 3,091,-369, entitled "Weighing and Mixing Hopper," by Walter J. Sackett, Sr. The weigh-blender 40 discharges into a surge hopper 46 of a screw conveyor 48 supported beneath the platform 44.

In use, the silo 10 of the bulk station 10 is charged with raw materials carried from the hopper cars 16 by the conveyor 12 and raised by the elevator 20 to the chute 22. The operator is able to selectively direct the several materials into the desired compartments 28 from his platform 44 by releasing the detented compartment selector lever 36 and thereby positioning the distributing spout 56 relative to one of the compartments 28.

When a blend of materials is to be delivered to a customer, the operator operates the weigh-blender 40 and notes the proportion of materials on scales 42 as they are released by the hydraulically operated compartment gates 34. The weighed and blended product is discharged into the surge hopper 46 and it is delivered by the screw conveyor 48 to bulk trucks 50 which may be positioned at optional locations as shown by reference numerals 50' or 50" in FIG. 2.

Should the customer wish to defer delivery of a material blend, provision is made in the bulk station 10 so that the operator can make up the order in the usual manner and store it in mixed form.

For this purpose, the screw conveyor 48 is provided with a reversible drive 134 as shown in FIG. 1. The flow of blended material from the surge hopper 46 is carried in a reversed direction in this case and discharged through a gate 136 into a chute 138 which connects with a receiving chute 140 at the lower end of the elevator 20.

The blended material is thence raised to the chute 22 and directed by suitable positioning of the distributing spout 56 into a funnel 142 within one of the compartments 28 of the silo 26.

Attached to this funnel 142 is a bypass chute 144 which is arranged to be linearly co-extensive with the chute 22. This chute 144 emerges from the silo 26 and empties the material into a temporary storage hopper 146. Thus, at this convenience, the customer is able to take delivery from the hopper gate 148 without interrupting other deliveries from the bulk station 10 at optional bulk truck locations designated by reference locations 50' or 50".

The funnel 142 and chute 144 occupy very little space and do not interfere with the normal storage use of the compartment 28 through which they pass.

It should be noted that the bulk station 10 as related occupies very little space considering the complex function it performs. Further the simplicity of operation on the bulk station 10 requires a minimum of personnel for efficient functioning.

Obviously, many modifications and variations of the present invention are possible in light of the above teachings. It is, therefore, to be understood that within the scope of the appended claims the invention may be practiced otherwise than as specifically described.

What is claimed is:

1. A multi-compartment bulk station type storage tank, comprising, means including a truncated cone having a plurality of vertically extending compartments radially arranged therein, support structure for supporting said cone in a downwardly facing elevated position, a multi-compartment silo formed of staves bound together with

hoops and mounted on top of said support structure in contiguous relationship with said cone, said silo being thereby demountable, selector means rotatably secured to the top of said silo, said selector means having a top-most stationary portion adapted to communicate with material supply means and a bottom swivel portion for directing material to a selected compartment, means including a hollow mast member positioned along the longitudinal axis of said storage tank and extending from said selector means to the truncated portion of said cone, guide means vertically arranged on the outer surface of said mast member for positioning walls defining said compartments, means including a rotating member located beneath said silo and having a connecting rod passing along the interior of said mast member to said selector means for operation thereof, and means including a compartment gate positioned at the bottom of each compartment in said truncated cone for selectively discharging material from desired compartments.

2. The multi-compartment bulk station type storage tank of claim 1, and in addition a shield attached to the swivel portion of said selector means and adapted to interfit with the top of said silo to form a rain-proof joint therewith.

3. The multi-compartment bulk station type storage tank of claim 1, and additionally gravity feed chute means communicating with said bottom swivel portion of said selector means for directing said material to a remote point for storage.

4. The multi-compartment bulk station type storage tank of claim 1, and additionally guide means vertically arranged on the inner surface of said staves for positioning the outer edges of said walls.

5. A multi-compartment bulk station type storage tank, comprising, means including a truncated cone having a plurality of vertically extending compartments radially arranged therein, support structure for supporting said cone in a downwardly facing elevated position, a multi-compartment silo demountably positioned on top of said support structure in contiguous relationship with said cone, selector means rotatably secured to the top of said silo, said selector means having a top-most stationary portion adapted to communicate with material supply means and bottom swivel portion for directing material to a selected compartment, means including a hollow mast member positioned along the longitudinal axis of said storage tank and extending from said selector means to the truncated portion of said cone, guide means vertically arranged on the outer surface of said mast member for positioning walls defining said compartments, means including a rotating member located beneath said silo and having a connecting rod passing along the interior of said mast member to said selector means for operation thereof, means including a compartment gate positioned at the bottom of each compartment in said truncated cone for selectively discharging material from desired compartments, and gravity feed chute means communicating with said bottom swivel portion of said selector means for directing said material to a remote point for storage.
